CLAIM

The ornamental design for a home fragrance dispenser, as shown and described.

DESCRIPTION

FIG. 1 is a perspective view of a home fragrance dispenser according to our new and ornamental design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dot broken lines represent the boundaries of the claimed design and form no part of the claim. The evenly dashed broken lines represent portions of the home fragrance dispenser that form no part of the claimed design.

1 Claim, 6 Drawing Sheets
